FOAM SPRAY ATTACHMENT FOR VACUUM CLEANERS

Egon Nohl, Wiener Neustadt, Austria, assignor to Rewo
Chemische Fabrik G.m.b.H., Steinau, Kreis Schluchtern,
Germany

Filed Dec. 14, 1965, Ser. No. 171

Term of patent 3½ years

(Cl. D9—2)

FIG. 1 is a perspective view of a foam spray attachment for vacuum cleaners, the opposite side being similar in appearance;

FIG. 2 is a front elevation of the foam spray attachment; and

FIG. 3 is a section through the upper left front of the foam spray attachment, taken along lines 3—3 of FIG. 1.

What is claimed is:

The ornamental design for a foam spray attachment for vacuum cleaners, as shown and described.
